United States Patent Office

Des. 184,954
Patented Apr. 21, 1959

184,954

TISSUE PAPER OR LIKE SHEET MATERIAL

Paul Adolf Müller, Herrliberg, Switzerland

Application November 9, 1955, Serial No. 38,811

Term of patent 14 years

(Cl. D59—2)

Fig. 1

Fig. 3

Fig. 1 is a top plan view of a tissue paper or like sheet material showing my new design;

Fig. 2 is an enlarged fragmentary view of the design shown in Fig. 1, and

Fig. 3 is an edge view of Fig. 2.

I claim:

The ornamental design for a tissue paper or like sheet material, substantially as shown.
